UNITED STATES PATENT OFFICE

LOUIS A. PARADISE AND EDWIN FREDERICK HUDDLE, OF MOLINE, ILLINOIS, AS
SIGNORS TO DEERE & COMPANY, OF MOLINE, ILLINOIS, A CORPORATION OF ILLINOIS

THRASHING MACHINE

Application filed May 21, 1927. Serial No. 193,128.

The present invention relates to thrashing machines and aims generally to provide an improved construction of machine capable of obtaining a more thorough thrashing of the grain. More specifically, one of the features of the invention is concerned with the handling and re-thrashing of the tailings and unthrashed heads, whereby there is a minimum loss of grain, even when the machine is operating under adverse conditions.

The adverse conditions to which we refer are those conditions commonly encountered in the field in the use of combined harvesters and thrashers, which cut and thrash the grain in one continuous operation. The present invention has been devised primarily for this type of machine, to the end of compensating for the unfavorable conditions under which these machines operate. As illustrative of such conditions, the machine frequently travels over rough or sloping ground which tips the machine either laterally or fore and aft. This results in the tipping of the separating shoes to an undesired degree, causing the grain and unthrashed heads to work over to the sides of the shoes or to feed improperly along the shoes, either of which conditions will adversely affect the normal separating functions of the shoes. Furthermore, owing to the fact that this type of machine is constantly turning and traveling in different directions in its movement in the field it is subject to the unfavorable action of any existing wind, which, in the different directions of travel of the machine, will blow crosswise thereof and at other angles adverse to the most efficient operation of the machine.

The particular improvements which enable us to compensate for these conditions, and thus to avoid objectionable loss of grain, reside principally in an arrangement whereby the tailings and unthrashed heads from both shoes are caused to pass through one or an indefinite number of repeated cycles until the thrashing of the heads is completed. Inasmuch as our invention has its greatest utility in these "combine" machines

we have shown it in such embodiment in the accompanying drawings, but it will be understood that the invention is not limited to this type of machine.

Referring to these accompanying drawings:

Fig. 1 is a fragmentary plan view of a typical combined harvester and thresher embodying our invention;

Fig. 2 is a side elevational view of the thrashing portion of the machine, the tailings elevator for the first and second shoes being illustrated in section;

Fig. 3 is a longitudinal sectional view through the thrashing portion of the machine; and

Fig. 4 is a fragmentary sectional view through the stubbleward side of the machine, taken on the plane of the line 4-4 of Fig. 3, and showing the discharge of the cleaned grain to the grain spout.

Combined harvesters and threshers are typically constructed with a main frame, on which is supported the thrashing mechanism, and an outwardly projecting harvester frame, on which is supported the harvester mechanism for cutting the grain. This main frame is represented by the two spaced frame bars 10 and 11 which are supported at their forward ends by a swiveled steering truck 12 in which is journaled a steering wheel 13. The rear portions of these main frame bars have suitable bearings or brackets 14 secured thereto which receive an axle 15 on which rear wheels 16 are mounted. The outwardly extending harvester frame is also usually supported by a wheel (not shown) mounted adjacent the outer end of said frame. These machines are generally pulled by a tractor hitched to the front end of the main frame.

The harvester portion of the machine consists of any conventional arrangement of sickle bar cutting mechanism and a reel for presenting the standing grain to such cutting mechanism. This harvester mechanism is all well-known, and hence we have not deemed it necessary to illustrate the details thereof. The grain cut by the sickle bar falls upon a laterally extending con-

veyor 17 which carries it into the main portion of the machine where the grain is dumped through the open side of a feeding hopper 18. Traveling in the bottom of this 5 hopper is a main feeding conveyor 19 which conducts the grain to the thrashing cylinder 21. This thrashing cylinder, and the other operating parts of the thrashing mechanism, are enclosed in a casing consisting of side 10 panels 23 and top panels 24, preferably reinforced by angle bars 25 which are secured at their lower ends to the side frame bars 10, 11.

Power for driving the thrashing cylinder 15 and the other operating parts of the machine may be derived from a power take-off on the tractor which pulls the machine, or it may be derived from a separate power plant located preferably at the front end of the 20 main frame. The latter arrangement has been shown, the internal combustion engine 26 representing such a power plant. From a pulley 27 on the engine crank shaft a belt 28 extends back to a pulley 29 on the thrashing cylinder shaft 31. The drive of the 25 feeding conveyor 19 is effected through a chain 32 on the stubbleward side of the machine which passes upwardly over a sprocket 33 mounted on the outer end of the conveyor drive shaft 34. This drive shaft carries the usual spaced sprocket wheels 30 within the feeding hopper 18, over which the side chains of the conveyor pass. The conveyor comprises any suitable belt having 35 slats 35 secured thereto for feeding the grain to the throat of the thrashing cylinder. The chain 32 is driven from an upper fan shaft 37, the stubbleward end of which carries a sprocket wheel 38 on the outer side of the 40 casing, over which this chain passes. On the harvester side of the machine, the shaft 37 carries a sprocket wheel 39 over which travels a chain 41 which is driven by a sprocket wheel 42 on the thrasher cylinder drive shaft 45 31. As the grain moves rearwardly on the feeding conveyor 19 it is beaten down and fed into the throat of the thrashing cylinder by a fan or beater 43. This member is mounted in the side wall of the feeding hopper and 50 is provided with a sprocket wheel 44 on the outer side of the hopper, over which wheel the chain 32 passes. The chain loops down around an adjustable sprocket wheel 45 suitably supported in a bracket 46, this latter sprocket wheel serving to take up slack 55 in the chain.

The thrasher cylinder 21 if of any preferred construction, operating in conjunction with a toothed concave 47, as is typical 60 of these thrashers. From the discharge side of the cylinder the straw is thrown up over a grating consisting of a series of closely spaced spring fingers 48. As the straw passes off this grating on to the straw walker 65 er 49, it is engaged by a rotating picker or

beater 51 which assists in the thrashing and separating process. The beater is mounted on a transversely extending shaft 52 projecting through both side walls of the casing. At the harvester side of the casing, 70 such shaft carries a sprocket wheel 53 over which passes the chain 41, whereby the beater is driven from the cylinder drive shaft 31. The straw walker 49 consists of a plurality of longitudinally extending 75 plates or bars 49', the upper edges of which are toothed to give a progressive feeding action to the straw. This straw walker is given an oscillatory throwing motion through its mounting on cranks formed in 80 two rotating shafts 54 and 55. The crank portions of these shafts engage in bearing blocks 56 secured to the under sides of the plates 49'. The oscillatory motion of the straw walker feeds the straw progressively 85 back toward the open rear end of the casing, and in such feeding action agitates the straw for the separation of the grain therefrom. The shaft 54 extends through the harvester side of the casing and supports a sprocket 90 wheel 57. The beater shaft 52 carries a small sprocket wheel 58 over which passes a chain 59, this chain extending down around the lower side of the relatively large sprocket wheel 57 for driving the shaft 54. 95

Extending under the thrasher cylinder and under the rear portion of the straw walker is a feeding plate or tray 61. Extending below the outer or rear end of the straw walker is a similar feeding plate or 100 tray 62. The bottoms of these feeding plates have stepped surfaces designed to impart a progressive feeding motion to the grain in the oscillation of such plates, the inner plate 61 being arranged to feed the 105 grain dropped thereon towards its rear edge, and the plate 62 being designed to feed the grain dropped thereon towards its front edge. The grain discharged from the contiguous edges of both plates falls upon the 110 inner end of a separating shoe 63. The two plates and the shoe are given oscillatory motion through rockers 64 disposed at each side of these elements. These rockers are pivoted at 65 to the frame of the machine 115 and have pivotal connection at their upper ends to the feeding plates 61 and 62, at pivot points 66 and 67. The lower portion of each rocker has pivotal connection with the shoe 63 at 68, and these lower ends of the rockers carry pivot pins 69 over which engage pitmen 71 disposed at each side of the machine. The forward ends of these pitmen have bearing blocks 72 which engage on the crank portions of a transversely 120 extending shaft 73 disposed below the frame of the machine and journaled in bearing brackets 74 secured to the under side of the frame. At the stubbleward side of the machine, this agitating shaft 73 carries a 125

sprocket wheel 75 over which passes a drive chain 76, such chain looping up around a driving sprocket 77 mounted on the stubbleward end of the beater shaft 52.

The front end of the feeding plate 61 extends under the concave 47 of the thrashing cylinder to receive the grain discharged directly from the cylinder, and this end of such feeding plate has swinging support on links 78 which have pivotal connection at their lower ends on hangers 79 secured to the bottom sides of the frame bars. The rear end of the outer feeding plate 62 has similar swinging support on links 81 pivotally mounted on the side walls of the casing. The rear portion of the shoe 63 also has swinging support on links 82 pivotally mounted on the frame. The shoe comprises the usual separating screen, through which the grain sifts down into a grain chute 83. The tailings from the end of the screen fall into a similar tailings chute 84. These chutes constitute a part of the shoe and oscillate therewith, the grain chute discharging into a trough 85 in which rotates a grain auger 86, and the tailings chute 84 discharging into a trough 87 in which rotates a tailings auger 88. A fan 89 is disposed forwardly of the shoe and has the outlet opening of its housing 91 discharging into the end of the grain chute 83. The fan projects a blast of air below and up through the shoe to blow the chaff and other light particles out through the open rear end of the casing. Such blast of air also assists in moving the unthrashed heads rearwardly along the shoe to the tailings end thereof. The fan is mounted on a shaft 92, one end of which projects from the harvester side 40 of the machine to receive a sprocket wheel 93, over which passes the chain 59, whereby the fan is driven from the beater shaft 52.

The grain discharged down through the chute 83 into the auger 86 is conveyed laterally thereby toward the stubbleward side of the machine where it is dumped into the lower boot end of an elevator 94. This elevator extends upwardly to the top of the machine and discharges the grain into a transversely extending auger 95, which, in turn, conveys the grain laterally across the width of a secondary or upper shoe 96 disposed above the straw walker 49. The upper sprocket wheel of the elevator 94 is driven by a shaft 97 to which is keyed a sprocket wheel 98. A drive chain 99 passes over this sprocket wheel and extends down adjacent the front end of the casing and passes over a sprocket wheel 101 mounted on the upper fan shaft 37. The drive which is thus transmitted to the elevator through the chain 99 also drives the lower grain auger 86, the shaft of which auger has operative connection with the lower sprocket wheel of the elevator.

The elevator dumps the grain into the outer end of a trough or tube 102 in which revolves the distributing auger 95. This auger is positioned adjacent the forward end of the upper shoe and distributes the grain transversely across the width of such shoe through a relatively narrow slot 103 extending longitudinally through the bottom of the trough 102. One side portion 102' of the trough is hinged at 104 to the stationary side portion thereof so as to permit this hinged section to swing outwardly. Such hinged section permits of widening of the discharge opening 103 in the event of clogging of the auger, and also affords easy access to the auger. The latter is driven through a sprocket wheel 105 (Fig. 2) mounted on the end of the auger shaft at the harvester side of the machine. A chain 106 passes over this sprocket wheel and up over a driving sprocket wheel 107 which is mounted on the end of a transversely extending shaft 108. This shaft is supported in bearing brackets 109 on the top of the casing, and at the stubbleward side of the machine it carries a sprocket wheel 111 over which passes the chain 99.

The upper shoe 96 preferably comprises a pair of riddles or screens 112 mounted in a suitable frame 113. This frame has swinging support on the lower ends of two pairs of pivoted arms 114 and 115. The arms 114 are keyed to a transversely extending shaft 116, to the outer end of which is connected an arm 117 having pivotal connection with a reciprocating pitman 118. A grain chute 119 slopes downwardly and forwardly below this upper shoe and discharges the grain sifting therethrough down into a grain auger 121 rotating in a trough 105 or tube 122. The tailings end of this upper shoe discharges into a trough 123 in which revolves a tailings auger 124. Mounted on the shaft 37 is a blast fan 125 which is suitably cased in above the thrashing cylinder 110 and is arranged to discharge a blast of air below and up through the shoe 96. This air blast sweeps any light refuse back to the discharge end of the casing, and assists in moving unthrashed heads and other tailings along the shoe to the tailings end thereof.

The grain which is discharged into the auger 121 constitutes the completely thrashed and cleaned grain, and this grain is conveyed laterally by the auger toward the stubbleward side of the machine where it is discharged into a grain spout 126 (Fig. 4). This grain spout extends at any suitable discharge angle relative to the machine and has a feeding auger 127 therein. Such auger is driven from the auger 121 through a universal joint coupling device 128 which connects the ends of the auger shafts. At the opposite side of the machine,

the shaft 121' of the auger 121 carries a sprocket wheel 129 around which passes the driving chain 106. The shaft 124' of the upper tailings auger 124 projects from 5 the stubbleward side of the casing (Fig. 4) and carries a sprocket wheel 131 around which passes the driving chain 99. A crank or eccentric 132 on this shaft, alongside the sprocket wheel 131, has operative connection with the pitman 118, whereby the latter is reciprocated for oscillating the second shoe 96.

The tailings from both shoes are conveyed by their respective augers 88 and 124 15 to the harvester side of the machine where they are discharged into an elevator 134 (Fig. 2). The trough or tube 87 of the lower tailings auger opens into the lower boot end 135 of the elevator, and the trough or tube 123 of the upper tailings auger 20 dumps into the elevator through a hood portion 136 formed in the upper wall of the elevator. The sprocket wheel 137, around which the lower end of the flight bar conveyor 134' passes, is keyed to a shaft 88', which may consist of an extending end portion 25 of the tailings auger 88, or which may be a separate shaft suitably coupled to this auger, the arrangement being such that the 30 auger will be driven from the elevator 134. At the upper end of the elevator the conveyor passes around a sprocket wheel 139 which is secured to the driving shaft 108. The conveyor is driven in the direction indicated, the upper stretch of the conveyor 35 passing down along an intermediate partition 141 upon which are discharged the tailings from the upper shoe. These tailings are conveyed down around the lower end 40 of the elevator where the tailings from the lower shoe are picked up, the tailings from both shoes being thence conveyed upwardly along the bottom wall of the elevator to a discharge opening in the upper end of the elevator. This discharge opening 45 communicates with a chute 142, which extends down into the feed hopper 18 and dumps the tailings upon the feeding conveyor 19 leading to the thrashing cylinder.

50 It will be seen from the foregoing description that while the machine is in operation all of the tailings from both shoes are being returned continuously to the thrasher cylinder for a repetition of the 55 thrashing and separating cycle. These tailings comprise any unthrashed heads, and any grain berries from which the white-caps, beards or husks have not been removed. It will be evident that these tailings 60 will be returned to the thrashing cylinder and will pass through repeated thrashing and separating cycles until such tailings have been completely thrashed. By returning the tailings from the first shoe directly 65 to the thrasher cylinder, instead of passing

these tailings up to the second shoe, there is avoided the possibility of the second shoe being overloaded in its separating capacity. Overloading of other parts of the machine has also been avoided in the present construction by returning the tailings from both shoes directly to the thrashing cylinder. If, through the inclination of the machine in traveling over sloping ground, or because of its operation under other adverse 75 conditions, any of the completely thrashed grain should get into the tailings, such grain will not be lost but will be returned to the thrashing cylinder for a repetition of the separating cycle.

80 What we claim as our invention and desire to secure by Letters Patent, is—

1. In a combined harvesting and thrashing machine, the combination of a thrashing cylinder, a conveyor for feeding the harvested grain to said thrashing cylinder, a straw walker receiving the straw from said cylinder, an oscillatory grain feeding pan disposed below said thrashing cylinder and said straw walker, a first cleaning shoe receiving the grain from said feeding pan, a second oscillatory grain feeding pan disposed below said straw walker and adapted to feed grain to said first cleaning shoe, a grain auger and a separate tailings auger 90 for said first shoe, a second cleaning shoe disposed above said straw walker, an elevator for conveying the grain from said grain auger up to said second shoe, a tailings auger for said second shoe and a tailings 100 elevator receiving the tailings from both of said tailings augers at different points and discharging the same to said feeding conveyor.

2. In a combined harvesting and thrashing machine, the combination of a thrashing cylinder, a conveyor for feeding the harvested grain to said thrashing cylinder, a straw walker receiving the straw from said cylinder, an oscillatory grain feeding pan 110 disposed below said thrashing cylinder and said straw walker, a first cleaning shoe receiving the grain from said feeding pan, a second oscillatory grain feeding pan disposed below said straw walker and adapted 115 to feed grain in opposite direction to said first pan whereby grain dropping from said entire straw walker is fed to said first cleaning shoe, a grain auger and a separate tailings auger for said first shoe, a second cleaning shoe disposed above said straw walker, an elevator for conveying the grain from said grain auger up to said second shoe, a tailings auger for said second shoe, a tailings elevator comprising an endless 120 flight bar conveyor for receiving tailings from said first shoe and adapted to carry said tailings along the under side thereof, said conveyor being adapted to receive tailings 125 on the upper side thereof from the 130

tailings auger for said second shoe and in advance of the reception of tailings from said first shoe, and a chute associated with said elevator adapted to discharge the tailings from both of said tailings augers to
5 said feeding conveyor.
